US0D1100849S

(12) **United States Design Patent** (10) Patent No.: **US D1,100,849 S**
(45) Date of Patent: ** Nov. 4, 2025

(54) **CONNECTOR**

(71) Applicant: **TE Connectivity Brasil Indústria De Eletrônicos Ltda**, Paulista (BR)

(72) Inventors: **Gustavo Bonucci**, Paulista (BR);
Rafael Kazuo Sato Toledo Leme,
Paulista (BR)

(73) Assignee: **TE Connectivity Brasil Indústria De Eletrônicos Ltda**, Paulista (BR)

(**) Term: **15 Years**

(21) Appl. No.: **29/872,144**

(22) Filed: **Mar. 7, 2023**

(30) **Foreign Application Priority Data**

Sep. 9, 2022 (BR) 3020220048577

(51) LOC (15) Cl. **13-03**

(52) U.S. Cl.

USPC **D13/147**

(57) **CLAIM**

The ornamental design for a connector, as shown and described.

DESCRIPTION

FIG. 1 is a rear, right and bottom perspective view of a connector in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the connector that form no part of the claimed design.

1 Claim, 7 Drawing Sheets
